UNITED STATES PATENT OFFICE.

JOHN W. GILMORE, OF NEW YORK, N. Y., ASSIGNOR TO CROUCH
& FITZGERALD, A CORPORATION OF NEW YORK.

GARMENT RECEPTACLE, RACK, AND THE LIKE.

No. 852,554.

Specification of Letters Patent.

Patented May 7, 1907.

Application filed September 11, 1906. Serial No. 334,112.

To all whom it may concern:

Be it known that I, JOHN W. GILMORE, a citizen of the United States, and a resident of the borough of Manhattan, county, city, and State of New York, have invented certain new and useful Improvements in Garment Receptacles, Racks, and the Like, of which the following is a specification.

This invention relates to receptacles for clothing and in particular to that type of receptacles which are provided with a hanger rack for garments, which rack may be moved back and forth for the purpose of making the garments readily accessible or out of the way at will.

An object of this invention is to provide a hanger rack with a free, swinging movement backward and forward relative to the garment chamber, while the rack is provided preferably with a single pair of tilting legs and other co-operating sustaining means. The term "free" is used as the antonym of "sliding".

A further object of the invention is to provide guiding and sustaining means for the rack which is of a practical nature and at the same time positioned entirely within the garment chamber for all positions of the garment rack. It is also desired to provide locking means for the garment hangers and also additional sustaining means for the rack when in its retracted position in the garment chamber.

A further object of the invention is broadly to provide suitable guiding and sustaining means for a swinging member, not necessarily a hanger rack, which is adapted to occupy two separate horizontal positions, comprising a single pair of tilting legs.

Further advantageous features of this invention will be apparent from the following description and claims, when read in connection with the accompanying drawings which illustrate an embodiment of the invention, form a part of this specification and in which:

Figure 1 is a front elevation showing a garment receptacle embodying the invention. Fig. 2 is a sectional elevation taken along line 2-2 of Fig. 1 and showing the hanger rack and sustaining means in side elevation. Fig. 3 is a top view partly in section along line 3-3 of Fig. 2 and also showing a sectional view of the receptacle lid or

closure. Fig. 4 is a detail view in section showing the hanger rack retracted and the receptacle closure in closed position.

Referring now more particularly to the drawings, 1 designates a garment chamber formed of suitable material and which may be stationary or portable as designated in the drawings. 2 designates a suitable closure or lid for the chamber 1. 3 designates a hanger rack of suitable construction and preferably provided with one or more rods 4, 5 and 6 for supporting garment hangers 7 and 8. The rack 3 is provided with two tilting legs 9 and 10 pivoted within the garment chamber respectively by pivots 11 and 12. These legs are also respectively pivoted to opposite sides of the hanger rack 3. The pivot for leg 10 is designated by 13, while a similar pivot is provided at the opposite side of the rack for leg 9. These pivots are located as shown near the rear of the rack and preferably between the central portion and rear edge thereof so that the rack has a tendency to tilt downward at its outer edge 14. The tilting legs 9 and 10 provide for a backward and forward swinging movement for the rack 3 which is limited backwardly by the rear wall 15 of the garment chamber 1 or by other suitable stops and is limited forwardly by the means 16 designated in the drawings as a flexible strap or stop but which might be of other suitable construction.

A rotation stop 17 is provided to prevent the downward tilting of the outer end 14 of the rack 3 when the rack is occupying its outward position as shown in Fig. 2. This rotation stop 17 is illustrated in the form of a strip or elongated stop secured by hinges 18 of leather or other suitable material made up in any suitable manner in recesses formed in the top interior surface of the garment chamber 1. These recesses are specifically designated as located each in a rib 20 running from front to back along the concavity of top 21 of chamber 1. Projecting fingers or hooks 22 are secured to the stop 17 to engage with the rear of the rack 3 so as to prevent the stop 17 swinging out of engagement with rack 3 when the parts are in position as shown in Fig. 2. This function might be accomplished solely by the corners of the recesses 19. The stop 17 is normally actuated by gravity and by the spring tendency of the

leather hinges 18 to assume the position designated in Fig. 2.

With the parts as shown in Fig. 2, it should be noted that the rack 3 is maintained in a substantially horizontal position by the legs 9 and 10 and the tops 16 and 17, all of these parts 9, 10, 16 and 17 comprising sustaining means for the rack 3. In this position, the stop 17 acts as a fulcrum to overcome the tilting tendency of the rack 3 about the pivots at the upper ends of the legs 9 and 10. In this position access both from the front and both sides is furnished for the rack 3 since all the sustaining parts for the rack are located entirely within the garment chamber 1. In this position garments may readily be applied to the rack 3 or may be removed therefrom.

To cause the rack 3 to occupy its retracted position as indicated by dotted lines in Fig. 2, it is necessary to apply external pressure to the rack, forcing it in, in which case the rack's frictional engagement with the stop 17 or its engagement with the hooks or fingers 22, if they are provided, swings the stop 17 up into the recesses 19. When moved into this retracted position the tilting legs 9 and 10 are substantially vertical as shown and the downward tilting of the outer end of the rack 3 is prevented by the rear edge thereof engaging with the top 21 of the garment chamber 1, which acts as a fulcrum to prevent rotation. In both the positions designated in Fig. 2, the tilting legs 9 and 10 serve as the sole means for holding up the rack from underneath. However, wedging supports 23 and 24 are provided on the lid or closure 2 to engage beneath the front edge of the rack 3 when the lid 2 is in closed position as designated in Fig. 4. This provision is of particular importance when it is desired that the garment receptacle be portable as in the case of a wardrobe trunk. The supports 23 and 24 relieve the legs 9 and 10 of a great deal of their strain and add greater endurance to the structure as a whole. But slight exertion is required to pull out the hanger rack since the tilting legs 9 and 10 necessitate a slight downward movement of the rack as it moves out of the garment chamber. On this moving out the rotation stop 17 drops down and automatically engages with the rear of the rack 3 to prevent its tilting from the horizontal. It should be noted that the rack thus has a free swinging movement and may be provided with enough play so as to avoid any possible binding due to hard usage of the receptacle.

The ribs 20 are provided with a facing 25 of suitable material, such as leather, which operates to engage the hooks 26 and 27 of the garment hangers when the rack is in its retracted and elevated position as shown in dotted lines in Fig. 2 and in full lines in Fig. 65 1. However, if the interior of the top 21 is

solid, as it may be, the leather facing may be applied to the top in strips properly positioned thereon over the ribs 4, 5 and 6. The broken lines in Fig. 1 designate a garment secured to the hanger 7.

It is to be understood that all suitable accessories such as locks, clasps, straps, hinges, etc. may be provided for the clothing receptacle.

Other obvious embodiments and modifications of the features described and illustrated are also within the scope of this invention.

What is claimed and what is desired to be secured by Letters Patent is:—

1. In a receptacle for clothing, a garment chamber accessible from the front; an elevated hanger rack for said chamber having a free swinging, in and out movement between a freely accessible position and a retracted position; sustaining and guiding means for said rack maintaining it substantially horizontal when in either its freely accessible or its retracted position, said means always located entirely within said chamber so that said rack will be freely accessible from the front and sides when in its freely accessible position; a closure for said chamber; and additional sustaining means in combination with said closure for supporting said rack when said closure is in closed position.

2. In a receptacle for clothing, a garment chamber accessible from the front; an elevated hanger rack for said chamber having a free, swinging, in and out movement between a freely accessible position and a retracted position; sustaining and guiding means for said rack maintaining it substantially horizontal when in either its freely accessible or its retracted position, said means always located entirely within said chamber so that said rack will be freely accessible from the front and sides when in its freely accessible position; a closure for said chamber; and additional sustaining means in combination with said closure for supporting said rack when said closure is in closed position.

3. In a receptacle for clothing, a garment chamber accessible from the front; an elevated hanger rack for said chamber having a swinging movement within and without said chamber; two sustaining tilting legs pivoted at their lower ends within said chamber and pivoted at their upper ends respectively to opposite sides of said rack near the rear edge thereof so that said rack has a tendency to rotate; a stop for limiting the outward swing of said rack; and a rotation stop for engaging the rear of said rack to maintain said rack in a horizontal position when swung from within said chamber to the limit of its outward movement.

4. In a receptacle for clothing, a garment chamber accessible from the front; an elevated hanger rack for said chamber having a swinging movement within and without said

chamber; two sustaining tilting legs pivoted at their lower ends within said chamber and pivoted at their upper ends respectively to opposite sides of said rack near the rear edge thereof so that said rack has a tendency to rotate; a stop for limiting the outward swing of said rack; and an automatically engaging and disengaging rotation stop for engaging the rear of said rack to maintain said rack in a horizontal position when swung from within said chamber to the limit of its outward movement.

5. In a receptacle for clothing, a garment chamber accessible from the front; an elevated hanger rack for said chamber having a swinging movement within and without said chamber; two sustaining tilting legs pivoted at their lower ends within said chamber and pivoted at their upper ends respectively to opposite sides of said rack near the rear edge thereof so that said rack has a tendency to rotate; a stop for limiting the outward swing of said rack; and an automatically engaging and disengaging hinged rotation stop for engaging the rear of said rack to maintain said rack in a horizontal position when swung from within said chamber to the limit of its outward movement.

6. In a receptacle for clothing, a garment chamber, accessible at the front and comprising a top interior surface provided with one or more recesses; a hinged stop held folded up in said recesses by a hanger rack but having a tendency to tilt downward out of said recesses; said hanger rack being provided with a pair of rearwardly pivoted tilting legs occupying a substantially vertical position when said hanger rack is holding said hinged stop folded in said recesses; said hanger rack having an outward and downward swinging movement on said tilting legs; means for stopping said movement of the hanger rack with the hanger rack in a position partly outside of said garment chamber and in suitable position so that said hinged stop, now released, may engage the rear of said hanger rack to prevent a downward tilting of the front of said hanger rack by operating as a fulcrum.

7. In a receptacle for clothing, a garment chamber accessible at the front and comprising a top interior surface provided with recesses; a hinged stop held folded up in said recesses by a hanger rack but having a tendency to tilt downward out of said recesses; said hanger rack being provided with a pair of rearwardly pivoted tilting legs occupying a substantially vertical position when said hanger rack is holding said hinged stop folded in said recesses; said hanger rack having an outward and downward swinging movement on said tilting legs; means for stopping said movement of the hanger rack with the hanger rack in a position partly outside of said garment chamber and in suitable

position so that said hinged stop, now released, may engage the rear of said hanger rack to prevent a downward tilting of the front of said hanger rack by operating as a fulcrum; and a hinged closure for said garment chamber provided with additional sustaining means for said rack.

8. A swinging member adapted to occupy two separate horizontal positions; a pair of tilting legs pivotally secured at their upper ends respectively to said member and back of the middle thereof, said member having a tendency to tilt downward at its outer edge; means limiting the tilting movement of said legs in each of two directions; means engageable and disengageable by the rear edge of said member to maintain the said member horizontal when the said tilting legs are at the extremity of their movement in one direction; and additional means to engage the rear edge of said member to maintain said member horizontal when said tilting legs are at the extremity of their movement in the opposite direction.

9. A swinging member adapted to occupy two separate horizontal positions; a pair of tilting legs pivotally secured at their upper ends respectively to said member and back of the middle thereof, said member having a tendency to tilt downward at its outer edge; means limiting the tilting movement of said legs in each of two directions; a hinged stop engageable by the rear edge of said member to maintain the said member horizontal when the said tilting legs are at the extremity of their movement in one direction; and additional means to engage the rear edge of said member to maintain said member horizontal when said tilting legs are at the extremity of their movement in the opposite direction.

10. A swinging member adapted to occupy two separate horizontal positions; a pair of tilting legs pivotally secured at their upper ends respectively to said member and near the rear edge thereof, said member having a tendency to tilt downward at its outer edge; means limiting the tilting movement of said legs in each of two directions; a hinged stop provided with rack engaging fingers engageable by the rear edge of said member to maintain the said member horizontal when the said tilting legs are at the extremity of their movement in one direction; and additional means to engage the rear edge of said member to maintain said member horizontal when said tilting legs are at the extremity of their movement in the opposite direction.

In testimony whereof, I have signed my name to this specification, in the presence of two subscribing witnesses.

JOHN W. GILMORE.
